UNITED STATES PATENT OFFICE.

KARL KIEFER, OF CINCINNATI, OHIO.

COLLAPSIBLE TUBE.

Application filed September 21, 1923. Serial No. 664,079.

My invention relates to collapsible tube containers such as are used for holding pastes, creams and similar substances, to be squeezed out through a neck at one end of the tube; the opposite end being left open in the manufacture of the containers, and the substance being filled into the container through this opposite end, and this end then being flattened and closed by a suitable seam or the like, in such a manner that the closure will resist opening effectively when the tube is squeezed, even when the neck is closed, so that there will be no accidental disruption of this closed end of the tube. Heretofore, this closed end has been reinforced, usually, by some kind of clip, or by a stiffer piece of material folded with the tube walls, or by a solder, or other added element, to insure against the accidental opening just alluded to.

The object of my invention is to effect a self-sustaining closure of this end of the tube which will effectively resist opening under the circumstances above described, without the use of any additional piece or substance, and which will permit of rapid formation, preferably by the use of automatic apparatus, whereby these closures may be effected with minimum expense. A further object is to provide such a closure with the requisite neatness of appearance. Other objects will appear in the course of the ensuing description.

I attain these objects by the device illustrated, for example, in the accompanying drawing, in which—

Figure 1 is a side elevation of a collapsible tube embodying my invention;

Fig. 2 is a side elevation opposite to that seen in Fig. 1;

Fig. 3 is an enlarged partial perspective view of the tube, the view corresponding to that of Fig. 1;

Fig. 4 is a partial perspective view of the tube, inverted as when being filled, and with the end flattened after filling, ready for the first stage of the closing operation;

Fig. 5 similarly illustrates this tube upon completion of the first stage of the operation;

Fig. 6 similarly illustrates this tube upon completion of the second stage of the operation;

Fig. 7 similarly illustrates this tube dur-

ing an intermediate part of the third stage of the operation;

Fig. 8 is a partial cross-section, much enlarged, on a plane corresponding to the line 8—8 of Fig. 3; and

Fig. 9 is a similar section illustrating a modification of my invention.

The collapsible tube 1 is of the usual well known construction, comprising the body 2 of soft metal, such as a lead or tin alloy, of very thin sheet formed into a seamless tube and having secured in one end the top 3 of similar metal, having a threaded neck on which is screwed the cap 4 which is removed to allow escape of the contents when the body 2 is squeezed or contracted. These tubes are supplied of circular cross-section from their tops 3 entirely to their opposite ends 5 (Fig. 4) which are left open for insertion of the contents while the tubes are inverted.

As illustrated in Figs. 4, 5 and 6, the initial stages of formation of the closure according to my invention are similar to the operations heretofore performed on such tubes. The tube having been filled to within a short distance of the open end 5, this end is flattened as seen in Fig. 4 until the two opposite sides 6 and 7 of this end lie closely together from one corner 8 to the other in straight parallel lines. Then these sides 6 and 7 are folded on a transverse line represented by the broken line A in Fig. 4, over in the direction of the arrow there shown, until the two portions of the outer surface of the side 6 lie closely together, as illustrated in Fig. 5, forming a rounded edge 9 and corners 10. Then the thus folded sides 6 and 7 are again folded in the same direction as indicated by the arrow in Fig. 5, on a second transverse line B just below the down turned end 5, so that the outer surface of the opposite side 7 now lies in against the outer surface of the side 6 with the end 5 up under the turn of the fold and the rounded edge 9 and corners 10 downwardly, as seen in Fig. 6; thus forming a new rounded edge 11 and new corners 12.

At this stage of the operation, as heretofore practised, some kind of clip or the like has been fastened astraddle of the edge 11, or soldering has been provided along the down turned edge 9 and at the corners 8 up in the fold. Such provisions are incon-

venient, especially involving complication in conjunction with rapid automatic filling and closing of these tubes, as is desirable in large output of preparations packed in such tubes. Some additional securing of these end parts is necessary, because the pressure of the contents against the simple repeated folds is sufficient to unfold them and allow escape of the contents at this end of the tube. I dispense with the use of such clips, soldering or the like, and avoid the use of any additional piece or substance, yet effect a closure which I find effectively resists opening, even though the tube be squeezed without removing the cap 4; continued squeezing of the tube resulting in bursting of the unfolded body part of the tube before failure of the closure.

This is accomplished by folding the seam formed as above described in direction opposite to that of the repeated folds just made, so that this last folding will involve both of the previously formed folds. I find that this is best accomplished by folding diagonally or obliquely along lines represented by the broken lines C in Fig. 6, in reverse direction as indicated by the arrows in that view; these lines of folding extending from each end of the seam at a point slightly below the down turned corner 10, upward toward the middle of the seam, but not quite meeting at the middle, leaving the seam unchanged in a short middle region 13. This operation is seen partly completed in Fig. 7; it being completed when the triangular corner parts have been folded down tightly against the outer surface of the side 7, upon which the closure will appear as shown in Figs. 1, 2 and 3, and as illustrated in cross-section in Fig. 8. Thus there is a double folding in one direction, straight across the tube, and oblique folding in reverse direction of the double folds, so that the double folds lie against one side of the tube in the middle region 13 and triangular triple folds lie against the opposite side of the tube from this middle region out to both edges, with the four thicknesses of metal of the double fold bent around the meeting sides 6 and 7 in the regions 14 extending for some distance in each direction from the middle region 13. Therefore, it is necessary for the pressure inside the tube to overcome the stiffness of the two sides 6 and 7 at their second fold which formed the edge 9, and in addition to this to overcome the stiffness of the four thicknesses bent around this edge for a distance exceeding one-half the width of the closure.

In the modification illustrated in Fig. 9, the final oblique folding will be understood to be the same as was described above, but previously to this the flattened together sides 6 and 7 have been folded three times entirely across the tube. That is, after the closure

has reached the stage illustrated in Fig. 6, the material is folded down once more entirely across just below the edge 9, forming a new rounded edge 15; and then the triple folds are folded obliquely in reverse direction, bringing the edge 15 obliquely along the side 7, with the edge 11 lying across the middle region of the side 6 and extending across to the opposite side as did the edge 11 in the double-folded example. Thus, there are triple folds at one side in the middle, and quadruple folds, triangular in shape, against the opposite side, with six thicknesses of metal bent around the meeting sides 6 and 7, so that the pressure must overcome the stiffness of the two bent sides 6 and 7 and of the six thicknesses bent around as described.

In either example, this arrangement will not result in excessive bulk, nor will the folding of the numerous thicknesses be difficult, as would appear from the exaggerated cross-sections of Figs. 8 and 9, because the metal of the tubes is very thin and soft, so that it can be bent very sharply, and either example will appear substantially as shown in Figs. 1 and 2. All of the folds may be made by suitable automatically operating mechanism, very rapidly, neatly and uniformly throughout practically the entire area of the seam, with the folds pressed very flat, so that the thickness of the closure is not noticeably thicker than the immediately adjacent unfolded sides of the tube, which sides, as is well known, diverge rapidly from the closure, taking the approximately cylindrical form a relatively short distance from the closure.

Other modifications of my invention may occur, such as a greater or less number of folds in either direction, or variation in the proportions or directions of the folds, or order of folding, or in other respects, and therefore, while I have somewhat specifically illustrated and described certain details as being preferable, I do not wish to be understood as being limited to such precise disclosure, but having thus fully described my invention,

What I claim as new and desire to secure by Letters Patent is:

1. A collapsible tube having an end seam consisting solely of the tube walls flattened together and sharply folded transversely, with opposite corner parts of the transversely folded walls sharply folded obliquely toward each other, whereby the thus folded walls are in intimate contact with each other throughout substantially the entire area of the seam, so that the seam, due to said intimate contact and said sharp folds, is self-sustaining.

2. A collapsible tube having an end seam consisting solely of the tube walls flattened together and sharply folded transversely,

with opposite corner parts of the transversely folded walls sharply folded obliquely toward each other in reverse direction to the transverse fold, whereby the thus folded walls are in intimate contact with each other throughout substantially the entire area of the seam, so that the seam, due to said intimate contact and said sharp folds, is self-sustaining.

10 3. A collapsible tube having a self-sustain-

ing closure consisting solely of intimately contacting portions of the tube walls having sharp folds which cross each other.

4. A collapsible tube having a self-sustaining closure consisting solely of intimately contacting portions of the tube walls having oppositely directed sharp folds which cross each other.

KARL KIEFER.
